No. 36,598.

Patented October 20, 1903.

UNITED STATES PATENT OFFICE.

MARSHALL B. LLOYD, OF MINNEAPOLIS, MINNESOTA.

DESIGN FOR A GO-CART BODY.

SPECIFICATION forming part of Design No. 36,598, dated October 20, 1903.

Application filed August 11, 1903. Serial No. 169,156. Term of patent 7 years.

To all whom it may concern:

Be it known that I, MARSHALL B. LLOYD, of Minneapolis, county of Hennepin, State of Minnesota, have invented a new, original, and ornamental Design for Go-Cart Bodies.

In the drawing the figure is a perspective of a doll go-cart embodying my invention.

I claim as my invention—
The ornamental design for a go-cart body, as shown.

MARSHALL B. LLOYD.

In presence of—
A. C. PAUL,
C. G. HANSON.
